(57) **CLAIM**

The ornamental design for a display screen or portion thereof with graphical user interface, as shown and described.

DESCRIPTION

FIG. 1 is a front view according to a first embodiment of our design;

FIG. 2 is a front view according to a second embodiment of our design;

FIG. 3 is a front view according to a third embodiment of our design;

FIG. 4 is a front view of according to a fourth embodiment of our design;

FIG. 5 is a front view of according to a fifth embodiment of our design;

FIG. 6 is a front view of according to a sixth embodiment of our design;

FIG. 7 is another front view of the first embodiment with alternative broken line subject matter;

FIG. 8 is another front view of the second embodiment with alternative broken line subject matter;

FIG. 9 is another front view of the third embodiment with alternative broken line subject matter;

FIG. 10 is another front view of the fourth embodiment with alternative broken line subject matter;

FIG. 11 is another front view of the fifth embodiment with alternative broken line subject matter; and,

FIG. 12 is another front view of the sixth embodiment with alternative broken line subject matter.

The outermost rounded broken line rectangles showing an electronic device illustrate environmental subject matter. The broken line showing a display screen, and all other broken lines showing portions of the graphical user interface, illustrate portions of the article. None of the aforementioned broken line subject matter forms part of the claimed design.
